UNITED STATES PATENT OFFICE.

FERGUS M. FERGUSON, OF HOBOKEN, NEW JERSEY, ASSIGNOR TO GEORGE H. CLARKE, OF BROOKLYN, NEW YORK.

GRATE-BAR.

SPECIFICATION forming part of Letters Patent No. 431,204, dated July 1, 1890.

Application filed October 7, 1889. Serial No. 326,227. (No model.)

To all whom it may concern:

Be it known that I, FERGUS M. FERGUSON, a citizen of the United States, residing at Hoboken, in the county of Hudson and State 5 of New Jersey, have invented a new and useful Improvement in Grate-Bars; and the following is declared to be a full, clear, and exact description of the same.

My invention is designed as an improvement upon the grate-bar set forth in Letters 10 Patent granted to C. D. Rogers June 22, 1886, No. 344,203. In this patent the grate-bar is composed of transverse bars and connecting bands or edge ties, between which there are 15 air-spaces, and below the transverse bars there are longitudinal supporting-ribs cast with the transverse bars, which ribs virtually divide the air-spaces into three parts—viz., central and outside air-spaces. Coal and 20 clinkers often lodge in and choke up these outside air-spaces, and the object of my present invention is to overcome this difficulty.

In carrying out my invention I construct a 25 grate-bar similar to the one described in the aforesaid patent, except that I arch the under sides of the edge ties, (adjacent to each of the narrow outer air-spaces,) to come above the top edges of the supporting-ribs, so that the edge ties are of narrower depth than the 30 depth of the parallel transverse bars. This lengthens and increases the space between the inner surface of the edge ties and the upper edge of each longitudinal supporting-rib, providing more room for ascending air 35 and descending particles of coal or clinkers.

In the drawings, Figure 1 is a plan view of a 40 grate-bar provided with my improvement. Fig. 2 is a side elevation of the same, and Fig. 3 is a cross-section at the line *x x*. The cast-metal grate-bar is composed of the 45 transverse bars *d*, the edge ties *f*, and the longitudinal supporting-ribs *a a*, beveled at their top edges. Between the lateral or transverse bars *d* there are air-spaces, which 50 are divided into the central portion *c* and the narrow outside portions *c'* by the ribs *a a*. These transverse bars *d* and the air-spaces between them may be of various shapes—such, for instance, as those shown in Figs. 1, 55 7, 8, 9, and 10 of the aforesaid patent—without departing from the spirit of this invention, the form shown in said Fig. 10 being

that shown in the drawings of the present case.

The connecting edge ties *f* are of narrower 55 depth than the depth of the transverse bars *d*, so that the under edges of the ties *f* are above the top edges of the supporting-ribs *a a*, thus forming arch-shaped openings *e*, each of which is adjacent to each of the narrow 60 outer air-spaces *c'*. The edges 4 of the metal of the ties *f* may be made at right angles to the vertical surfaces of the tie; but I prefer to taper the part, as shown in the cross-section 3. The edge ties *f* being of less depth 65 than the bars *d*, and their under edges being above the top edges of the ribs *a*, lengthens the air-spaces between the inner surface of the ties and the upper edges of the longitudinal ribs, and at the same time increases 70 the area through which clinkers, cinders, and ashes may pass freely into the ash-pit under the grate-bar without the risk that heretofore existed of clogging up such air-spaces. In 75 consequence of the under surfaces of the edge bars *f* being above the top edges of the supporting-ribs *a* the openings for the escape of ashes is narrowest between the top of the V-shaped surface of the ribs *a* and the lower edges of the edge bars, and ashes and 80 clinkers do not wedge into the opening, but fall away. Where the lower edges of such bars *f* are in line with the bottom of the V-shaped surfaces of the ribs, as in bars before 85 made, the openings are contracted in such a way that ashes and clinkers wedge therein.

I claim as my invention—

The improved grate-bar herein described, the same consisting of the longitudinal supporting-ribs *a a*, beveled at the top edges, the 90 parallel transverse bars *d* and the edge ties *f*, forming the fire-surface, said edge ties *f* being of narrower depth than the depth of the transverse bars, and their under edges being above the top edges of the supporting-ribs, 95 substantially as and for the purposes set forth.

Signed by me this 3d day of October, A. D. 1889.

F. M. FERGUSON.
